US0D1070567S

(12) **United States Design Patent** (10) **Patent No.:** **US D1,070,567 S**
(45) **Date of Patent:** **** Apr. 15, 2025**

(54) **TENSION ANCHOR**

(71) Applicant: **SAYFA R&D PTY LTD**, Boronia (AU)

(72) Inventors: **Murray Voss**, Boronia (AU); **Barry Voss**, Boronia (AU)

(73) Assignee: **SAYFA R&D PTY LTD**, Boronia (AU)

(**) Term: **15 Years**

(21) Appl. No.: **29/879,626**

(22) Filed: **Jul. 11, 2023**

(30) **Foreign Application Priority Data**

Jun. 20, 2023 (AU) 202314018

(51) **LOC (15) Cl.** **08-05**

(52) **U.S. Cl.**

USPC **D8/354**; D25/199
